UNITED STATES PATENT OFFICE

THOMAS G. MELISH, OF CINCINNATI, OHIO

FLOUR SIFTER

Application filed July 3, 1930. Serial No. 465,608.

This invention relates to a type of sifter designed especially for household use, to be used in the sifting of such products as flour and the like.

An object of this invention is to produce such a sifter as will bring about a sifting operation in which the resultant sifted product is of greater purity than is produced from other sifters of this general type, in which my improved construction has resulted in a sifter of materially improved and simplified operation permitting of its use by one hand without separate manipulation of the fingers thereof to sift the flour while simultaneously holding the sifter, and in which an improvement consists in the elimination of pockets and openings within which flour may accumulate and become stale or through which flour may leak and become spilled or wasted, as well as to produce a sifter in which all possible clogging of the mechanism thereof is prevented.

These and other objects are described in the following specification and illustrated in the accompanying drawing, in which:

Fig. 1 is a plan view of a sifter embodying my invention.

Fig. 2 is a sectional elevation thereof, taken on the line 2—2 of Fig. 1.

Fig. 3 is an enlarged fragmental sectional view for the purpose of disclosing details of my improved construction, the enlargement being that of the lower right hand portion of the sifter as shown in Fig. 2.

Fig. 4 is a fragmental perspective view upon a somewhat enlarged scale, showing a detail of my improved sifter, being a portion of the lower left hand part of the sifter to disclose the mounting of one of the agitator elements thereof.

My improved sifter consists of a tubular body or shell 5 which is open at both ends, the lower end being intercepted with an upper sifter screen 6 and a lower sifter screen

7. An annular inwardly extending shoulder 8 provides support for the metal-bound edge 9 of the lower screen 7. Between screen 6 and screen 7 is a secondary or spacer shell 10 which forms an inner collar upon the upper edge of which the metal-bound rim 11 of

upper screen 6 rests. In order that flour or other products to be passed through the screens, may be caused to do so, I have provided the respective agitators 12 and 13 on the screens 6 and 7. Each of these agitators is preferably made of wire and is bent to the substantially elliptical shape shown in Fig. 1, with a middle finger 14 provided to increase the efficiency of the sifter operation. The curved sides 15 and 16 of the agitator on each screen, are curved to the radius of the inner curvature of the sifter body so that when the agitators are moved across the screen from side to side, as suggested in dotted lines in Fig. 1, no portion of the screen will be omitted in the sifting operation. In order that this side to side motion of the agitators may be accomplished, I have mounted them pivotally in the shell, as follows:

Agitator 6 is provided with an upturned shank or shaft 17 which is at right angles to the agitator and lies against the side of the sifter shell so that it is held against this side by bearing lugs 18 and 19 located respectively at substantial top and bottom positions by being fastened to the shell as suggested in Fig. 2. The upper end of shank 17 is turned outwardly to form an extension 20 at right angles to shank 17 and thence downwardly to form a handle-bearing portion 21 upon which the handle 22 is mounted for rigid attachment thereto as shown by the embedded dotted line positions in Fig. 2. At the lower end of portion 21 an extension 23, corresponding to extension 20, terminates in a short shank, shaft or offset 24 turned downwardly and from which at right angles the lower agitator 13 extends to lie parallel to and to operate over screen 7. Lower shank or shaft 24 is positioned to lie back of spacer shell 10 so that it occupies the annular space 25 provided between this shell and the body shell, thereby affording a bearing for the shaft. In this manner the lower agitator is kept in position with shaft 24 held against the inner wall of the body shell, as particularly shown in Fig. 4, and side to side movement of the lower agitator is obtained by rocking extension 23 in the mounting hole which it occupies in the body shell.

It is quite obvious that operation of the sifter is very simple in that it is but necessary to grasp the handle 22 and to shake the sifter from side to side so that the body will 5 pivot on the shafts 17 and 24 and thereby cause relative movement of the agitators 12 and 13 in association with the screens 6 and 7. It is at this point that the function of the secondary shell 10 becomes apparent. 10 Were it not for the fact that this shell is so shaped as to direct all the flour from screen 6 onto the meshed portion of screen 7, an accumulation of flour would form in and about the space, pocket or annular groove 15 between metal-bound edge 9 and the inner wall of body shell 5. Because of the inaccessibility of this space between the two screens, whereby thorough cleaning could readily be accomplished, such an accumulation of sifted 20 material would result in an unsanitary condition and be likely to cause stale or mouldy flour to become loosened therefrom and drop into the sifted batch. The secondary shell 10 prevents this by keeping all flour away 25 from this pocket and directing it onto and through screen 7. Thus, the shell 10 performs a triple function in that it maintains the spaced relation of screens 6 and 7, as well as operates to retain shaft 24 against 30 the inner wall of shell 5, and also serves to prevent the accumulation and formation of a stale, moldy and unsanitary deposit of sifted material in and about the rim of the screen and body shell.

35 Having thus described my invention, what I claim is:

1. In combination in a sifter, a body shell open at both ends, screens across the shell adjacent to one end, a secondary shell within 40 the body shell, spaced therefrom and spacing the screens apart, an agitator on each screen, a shaft on each agitator at a right angle to the plane of the agitator and cooperating screen, said shafts occupying and adapted to 45 reciprocate in the same axial position, a bearing in the body shell above the screens, said bearing mounting one of the shafts, a bearing in the body shell between the screens, said second mentioned bearing mounting the other 50 of the shafts between the shells, arms from the shafts extending from the body shell, and a handle mounted by the arms for lifting the sifter and moving the agitators relatively to the screens.
- 55 2. A sifter comprising a body shell, screens across the shell at one end, a secondary shell within the body shell and spacing the screens apart, an agitator on each screen, bearings in the body shell and pivoting the agitators 60 therein, the bearing for one agitator being located above the screens, the bearing for the other agitator being located between the screens to pivot it back of the secondary shell, arms extending from the agitators to a position 65 beyond the body shell, and a handle

rigidly connected with said arms, whereby the sifter may be lifted and the agitators caused to function relatively to the screens.

In testimony whereof I hereunto affix my signature.

THOMAS G. MELISH.
